UNITED STATES PATENT OFFICE.

JOHN M. SEBOLD, OF PHILADELPHIA, PENNSYLVANIA, ASSIGNOR OF ONE-HALF TO WILLIAM SCHREINER, OF SAME PLACE.

IRONING-BOARD.

SPECIFICATION forming part of Letters Patent No. 400,799, dated April 2, 1889.

Application filed July 7, 1888. Serial No. 279,283. (No model.)

To all whom it may concern:

Be it known that I, JOHN M. SEBOLD, a subject of the King of Bavaria, and a resident of the city and county of Philadelphia, State of Pennsylvania, have invented a new and useful Improvement in Ironing-Boards, which improvement is fully set forth in the following specification and accompanying drawings.

My invention relates to improvements in ironing-boards; and it consists of the mechanism described and claimed for firmly and reliably securing the board in place.

Figure 1 represents a side elevation of an ironing-board embodying my invention. Fig. 2 represents a bottom plan view thereof.

Similar letters of reference indicate corresponding parts in the two figures.

Referring to the drawings, A represents an ironing-board of usual form and construction. Secured to the under side of the board near one end thereof are ears B, to which is pivoted a forked or bifurcated clamp, C, one end of which has noses a, for engagement with a ledge, b, on the wall of an apartment, and the other end has a heel, b', for engagement with the edge c of the head D of a lever, E, which is pivoted to the under side of the table, it being seen that the clamp C has a horizontal axis and the lever has a vertical axis. Consequently the clamp is capable of vertical motions and the lever of lateral or horizontal motions. The edge c of the head is spirally curved and serrated.

The operation is as follows: The end of the table above the clamp C is rested on the ledge b, so that the noses of the clamp come below the same. The lever is now rotated, whereby its head rides in a circle over the heel b' of the clamp, and owing to the spiral nature of said edge the heel end of the clamp is de-

pressed and the nose end consequently raised and forcibly pressed against the ledge, so that the table is clamped to the ledge and firmly held thereon. Owing to the serrations of the edge the head is prevented from slipping or returning to its first position.

By applying proper force to the lever it may be rotated, so as to relieve the clamp of the pressure of the head D, whereby the hold of the clamp on the ledge is released and the table may be removed.

The outer end of the table may be sustained on a prop, as shown.

It is evident that the ledge may be secured to an upright and the latter connected with a base, as shown in dotted lines, this construction being desirable where a ledge may not be conveniently attached to a wall.

When the table is removed, it will be found that the clamp and lever occupy small space on the under side thereof.

Having thus described my invention, what I claim as new, and desire to secure by Letters Patent, is—

1. The clamp C, with a nose and heel, and the tightening-lever E, having a spirally-curved and serrated edge, c, said parts being combined substantially as described.

2. An ironing-board having ears on the under side thereof, a forked clamp pivoted in said ears and having two noses adapted to engage a supporting-ledge and provided with a heel, and a rotary lever with a head having inclined and serrated contact-face, said parts being combined substantially as described.

J. M. SEBOLD.
